CLAIM

The ornamental design for a face gear, as shown and described.

DESCRIPTION

FIG. 1 is a front perspective view of a face gear showing our new design;

FIG. 2 is a rear perspective view thereof;

FIG. 3 is a front view thereof;

FIG. 4 is a rear view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion illustrated in circle 9 in FIG. 1.

The broken lines shown in the drawings are included for illustrative purposes only and form no part of the claimed design.

1 Claim, 7 Drawing Sheets

Related U.S. Application Data

continuation-in-part of application No. 13/737,713, filed on Jan. 9, 2013, which is a continuation-in-part of application No. 12/760,988, filed on Apr. 15, 2010, now Pat. No. 8,353,800, and a continuation-in-part of application No. 12/814,905, filed on Jun. 14, 2010, now abandoned.
